UNITED STATES PATENT OFFICE.

PAUL ARBON, OF TULSA, OKLAHOMA.

CONSTRUCTION AND ARRANGEMENT OF COLLAPSIBLE JETS.

Application filed April 16, 1924. Serial No. 706,932.

To all whom it may concern:

Be it known that PAUL ARBON, a subject of the King of Great Britain, residing at Tulsa, in the county of Tulsa and State of Oklahoma, has invented certain new and useful Improvements in Construction and Arrangement of Collapsible Jets, of which the following is a specification.

This invention relates to the construction and arrangement of two jet elements for use in the elevation of oil by means of external pressure.

More specifically, the present application includes the particular construction of two different jet elements, one fixed and the other collapsible, and the arrangement of such jet elements in a well with relation to a packer, it having been determined by experiments that certain types of wells, as for instance, where there is insufficient gas pressure to lift the fluid or where water is showing, necessitate the use of such jet elements as herein-after more fully described.

The jet members include in both instances a series of sets of unrestricted inclined ports of comparative negligible diameter these ports being in the instance of the collapsible jet capable of being closed by a downward movement of the casing and consequent movement of one of the elements comprising same.

The function and use of the various component parts heretofore mentioned will more clearly hereinafter appear by reference to the accompanying drawing forming a part of this specification and wherein like numerals of reference designate corresponding parts throughout the several views in which:—

Fig. 1 is a vertical sectional view through a well showing the arrangement of the jets.

Fig. 2 is a vertical sectional view through the collapsible jet.

Fig. 3 is a transverse section through the body member of the collapsible jet, and

Fig. 4 is a vertical sectional view through the plain jet.

Referring now to the particular construction, and arrangement of parts, attention is directed to Fig. 1 in which is illustrated a conventional well including the elements of the present invention. In this illustration,

the casing is indicated by reference character 1, the tubing at 2, and the casing head 3. A packer 4 is shown between the tubing 2 and the casing 1, and this packer acts to form a lower chamber 5 and upper chamber 6, within the casing.

At suitable points in the tubing above the packer 4 are arranged the plain jet 7 and the collapsible jet 8, the former being shown in detail in Fig. 4, and the latter in Figs. 2 and 3.

The construction of the jet 7 which in use is the main working jet, comprises a suitably fixed body having a central longitudinal passage of reduced diameter at 9 which tapers outwardly at its opposite ends at 10 and 11 to the internally threaded cylindrical ends of the tubing 2.

To permit the convenient drilling of the jet passages 15, the outer face of the jet body is formed with circumferential lateral shoulders 16 and 17. Suitably spaced according to the specification of the particular jet as determined by the intended application and use, which obviously will alter according to the type of the well and nature of the field in which the well is located. This variation will also apply in connection with the diameter of the jet. With further reference to the shoulders 16 and 17, attention is called to the fact that the diameter of the body of the jet is reduced uniformly from the shoulders 17 downwardly. The portion of the jet body below the shoulder 16 is tapered outwardly at 18 sufficiently to permit movement of the drill in the proper direction.

The collapsible jet 8 includes the tubular body portion 19 formed with the inwardly projecting annular flange 20 and the internally threaded wall 21. The portion 19 is formed with a plurality of sets of inclined ports 22. Within the tubular body 19 travels the valve member or jet closing means in the form of a headed tube, the head portion 23 of which is of sufficient diameter to move freely within the body 19 and at the same time properly seal the ports 22. The shank 24 of the valve member is in substance a conventional tubing section, and corresponds in shape and diameter to the adjacent tube section utilized in the elevation of the oil. The upper end of this tube is threaded to

engage the usual coupling member. Attention is directed to the fact that the upper shoulder and the lower face of the enlarged head 23 are tapered to form annular bearing surfaces. The upper bearing surface 26 engages the corresponding face formed on the under surface of the inwardly projecting flange 20 and the lower bearing surface 27 engages the beveled upper face of the lower element of the coupling member of the collapsible jet. This lower element of the collapsible jet is a combined coupling for connecting the adjacent tube section and an adjustable stop or seat for the valve member 23. The lower element comprises a tubular section externally threaded at its upper end 25 to engage the interior threads 21 of the body section, and as previously stated, is formed at its upper end with a tapered seat portion to receive the valve face 27. The lower end is slightly enlarged and internally threaded at 28 to engage the adjacent pipe section as shown more fully in Fig. 1.

Having thus described the particular construction of the various members forming a part of this invention, it will now be more obvious as to the use and operation of same.

For lifting fluid with compressed air or compressed gas such as would be necessary where there is insufficient gas pressure within the well to lift the fluid or where the capacity of a well is larger than can be obtained by the pump and again in a field that is showing water and it is necessary to keep the water down to save other wells in the vicinity from being ruined; for this purpose two jets are used, one above the other. The top or collapsible jet is placed approximately five hundred feet below the level of the fluid and the lower or plain jet three hundred feet below the collapsible jet and the packer is usually set in the last joint of the casing. Air is introduced through a stuffing box casing head into the well between the casing and tubing. Its first outlet is through the ports of the upper jet which are open, the air almost immediately elevates the fluid and the standing level of the well will commence to fall until the permanent or working level is reached; at this point the well will usually cease to flow as there is insufficient fluid above the jet and slippage is taking place (air flowing through the fluid). The tubing should now be lowered to allow the upper jet to collapse and close the ports which will result in the lower or plain jet being thrown in action. By this method of stepping down the fluid one is able to eliminate the high pressure air compressors that are necessary with other forms of air lifts.

It is practically impossible to advise where to set the jets, as every field varies as to gravity and again every well will vary as to capacity and working level. Some wells

will exhaust so rapidly that even the lower jet will be exposed, while with others the standing level will be so near the working level it will not be necessary to lower the tubing to close the upper jet. The efficiency, however, can be easily determined at the tank or mouth of the well as the flow should be steady and constant.

What I claim as new and useful and desire to secure by Letters Patent is:—

1. A collapsible jet comprising a ported tubular body portion, a sleeve valve reciprocating in said body to close the ports when in lowered position and open said ports when in upper position, means formed integral with the body for limiting the upward movement of the valve, and an adjustable stop for limiting the downward movement.

2. A collapsible jet comprising a body portion, nozzles therein, a solid-walled closure for said nozzles moving in said body, means formed integral with the body for limiting the upward movement of said closure and an adjustable stop for limiting the downward movement of said closure formed with an internally threaded extension.

3. A collapsible jet comprising a perforated body portion having an inwardly tapered flange at its upper end and a stop at its lower end formed with a conical valve seat, a valve member arranged within said body for movement to seal said perforations and adapted to engage said valve seat.

4. An apparatus for elevating oil comprising a casing, an eduction tube, a packer between said casing and eduction tube, a fixed jet adjacent said packer, and a collapsible jet above said fixed jet.

5. An apparatus for elevating oil comprising a casing, an eduction tube, a packer between said casing and eduction tube, a fixed jet adjacent said packer, and a collapsible jet member above said plain jet including a body portion formed with ports and means for closing said ports.

6. An apparatus for elevating oil comprising a casing, an eduction tube, a packer between said casing and eduction tube, a fixed jet adjacent said packer, and a collapsible jet member above said plain jet including a body portion formed with ports and means for closing said ports operated by the movement of the eduction tube.

7. An apparatus for elevating oil comprising a casing, an eduction tube, a packer between said casing and eduction tube, a fixed jet adjacent said packer, and a collapsible jet member above said plain jet including a body portion formed with ports and means for closing said ports operated by the downward movement of the eduction tube.

8. An apparatus for elevating oil comprising a casing, an eduction tube, a packer be-

tween said casing and tube, a collapsible jet and a fixed jet between said collapsible jet and packer comprising a body formed with a plurality of sets of ports.

5 9. An apparatus for elevating oil comprising a casing, an eduction tube, a packer between said casing and tube, a collapsible jet

and a fixed jet between said collapsible jet and packer comprising a body formed with a plurality of sets of inclined ports radiating 10 upwardly from horizontal flat faces formed in the jet body.

In testimony whereof I affix my signature.

PAUL ARBON.
